FIREPLACE HEATER

Oscar B. Leibst, Seattle, Wash.

Application July 1, 1952, Serial No. 296,538

1 Claim. (Cl. 126—121)

This invention relates to fireplace heaters, and particularly to adjustable furnaces for disposition in varying sized fireplaces.

In the practice of heating rooms by fireplaces, it is important to provide adjustable furnaces for disposition therein which may be easily connected and permit expansion thereof by heat without damage to the fireplace or the furnaces. It is also important to provide a grate in the furnace for burning various kinds of fuel and formed of tubular bars for passage of air therethrough, such air to be heated by the bars during the passage, and to be thereafter returned into the room for heating the same with means for preventing smoke from entering the room.

It is therefore one of the objects of this invention to provide a grate for supporting burning fuel and formed of a plurality of tubular bars having their front ends opening from the room in front of the fireplace and having their rear ends opening into a heating chamber disposed in the back of the fireplace. Together with the flue extended from the top of the chamber upwardly and outwardly and braced against the top arch of the fireplace, with the springs for supporting the front ends of the bars resiliently to permit expansion when heated below the arch.

A further object is to provide a duct with one end thereof opening into the room and the rear end extended into the heating chamber and upward therein to a point above the level of the grate bars, the said duct having a fan at the outer end for driving air through the duct and into the chamber for drawing air through the bars for heating the same, and also for discharging heated air from the chamber into the room.

A still further object is to provide an upstanding guard or fender along the top of the outer ends of the bars for retaining the fuel and having a sloping outer face plate for diverting drafts of air from the room upward into the chimney for providing a screen in front of any smoke to prevent the same from entering the room and for carrying the smoke upward through the chimney.

With these and other objects to be hereinafter stated I have exemplified my invention by the accompanying drawings of which: Figure 1 shows a front elevation of the furnace assembly. Figure 2 indicates a top plan of the lower portion thereof taken on line 2—2 of Fig. 1. Figure 3 is an end view taken from the right hand direction and Figure 4 is a section view taken on line 4—4 of Fig. 1.

Like numerals on the different figures represent like parts. Numeral 10 indicates a series of tubular bars having their front ends 10' opening from the room and their rear ends 10" opening into and connected with a heating chamber 13 in the rear of a fireplace. A bar 11 across the front ends of the bars connect the same with spaces between the same for air passage for burning the fuel. The assembled bars forming the grate 12 for a fireplace. The chamber 13 is formed by rectangular casing to be disposed in the back of the fireplace for receiving the air in heated condition after passing through the bars. The front wall 13' of the chamber also provides a wall or guard to retain fuel on the grate and is heated by the fire in front which increases the heat in the air from the bars.

Centrally from the chamber is an upraised flue 14 carried upwardly and forwardly to the top of the fireplace and outwardly along and against the arch 15 of the fireplace and is preferably provided with a box 15 around

2

the mouth 16 of the flue for discharging the heated air into the room which may be regulated by ordinary grill 16'. The lower portion of the flue is preferably rectangular in cross section, but rounded along the top 14' to prevent obstructing upward flow of smoke into a chimney 17.

Helical springs 18 are mounted beneath the outer ends of the grate bars for resiliently binding the top of the flue against the arch of the fireplace to prevent any smoke passing outward above the flue into the room and particularly to permit the bars and assembly to expand downward from the arch when heated without injury to the assembly, and also to maintain the bars in spaced relation above the floor and the fireplace for entry of air drafts for the fires and to provide space for any ash tray 19. Tubular guides 18' and 18" are telescopically mounted around the springs to retain the same in vertical positions and to permit the springs to expand and contract therein.

A rectangular baffle or fender 20 is connected across the outer ends of the bars to prevent the fuel and fire from entering the room, and particularly for supporting a face plate 21. This plate is maintained in spaced relation in front of the fender and obliquely therewith sloping upwardly and inwardly for diverting drafts of air upwardly and inwardly across the front of the fire-place for a screen in front of any smoke behind the same and to prevent the smoke from entering the room and to direct the same upward through the chimney.

It will be understood that air when heated by passing through the bars by suction from heated air in the chamber flowing upward in the flue will mingle and rise from the top of the flue and mouth 16 thereof into the room to some extent, but in order to increase the flow of such heated air in the room a duct 22 is mounted along one end of the grate and extended laterally into the base of the heating chamber 13, and upwardly therein as 22'. Any ordinary fan indicated as 23" is preferably mounted for operation at the outer end of the duct for driving air through the same. The fan may be located in a casing 23 on a shaft 23' from a motor indicated by 24, whereby any desired current of air may be forced into and upward through the flue, and outward from the mouth 16 into the room in heated condition, by the bars and from the front wall of the chamber.

For accelerating the suction by the air from the duct for drawing in air through the bars and the heated air from the chamber the top of the duct is carried to a point above the level of the grate bars to prevent outflow through the bars, and there provided with a relatively narrow rectangular mouth 25 near the front wall of the flue for passage of air currents from the fan. A relatively short distance below the mouth 25 a gash is disposed across the inner wall of the duct providing a lip 27 which is extended outward to provide a venturi like neck 28 along the wall 26 of the duct. In operation when the air current is forced from the mouth of the flue it siphons or draws the heated air from the chamber and lower portion of the flue through the neck 28 and carries the same upward through the flue into the room at the desired speed and temperature.

Having described my invention I claim as new for Letters Patent:

A heating unit for a room, comprising a fireplace, an arch across the top thereof, a plurality of bars connected in parallel relation forming the grate for the fireplace, said bars having their outer ends open for drawing air from a room and their rear ends opening into a heating chamber in the back of said fireplace, a chimney above the fireplace, a heating chamber first mentioned having a flue extended upward therefrom and outward in the fireplace and adapted to open into the room, a duct having one end thereof adapted to open into the room and extending rearwardly into the heating chamber and upwardly therein to a position higher than the rear ends of the bars for discharging currents of air upwardly into the flue, springs disposed beneath the outer ends of the bars for resiliently binding the upper end of the flue against the arch of the fireplace to prevent smoke from passing outward from above the flue and to permit the flue and grate bars to expand downwardly when heated without injury thereto and to facilitate the use of the

unit in fireplaces of varying elevations vertically, a fender attached to and upstanding from the front of the bars for supporting a face plate, a face plate first mentioned diagonally disposed in front of the fender disposed inwardly and upwardly for diverting drafts of air from the room inwardly and upwardly in the fireplace and for providing a shield in front of any smoke and for carrying the same upward from said chimney and to prevent smoke from entering the room.
